(57) **CLAIM**

The ornamental design for a vaping apparatus as shown and described.

DESCRIPTION

FIG. 1 is a top, front, and right side perspective view of a vaping apparatus according to the novel design.

FIG. 2 is a bottom, rear, and right side perspective view of the vaping apparatus depicted in FIG. 1.

FIG. 3 is a front view of the vaping apparatus depicted in FIG. 1.

FIG. 4 is a rear view of the vaping apparatus depicted in FIG. 1.

FIG. 5 is a right side view of the vaping apparatus depicted in FIG. 1.

FIG. 6 is a left side view of the vaping apparatus depicted in FIG. 1.

FIG. 7 is a top view of the vaping apparatus depicted in FIG. 1; and,

FIG. 8 is a bottom view of the vaping apparatus depicted in FIG. 1.

The broken lines included in the drawings depict elements of the vaping apparatus that are not part of the claimed design.

1 Claim, 8 Drawing Sheets
